UNITED STATES PATENT OFFICE.

CHARLES E. McMANUS, OF NEW YORK, N. Y.

LOCKING ATTACHMENT FOR CORK-ROD BAKERS.

1,412,125.

Specification of Letters Patent. Patented Apr. 11, 1922.

Application filed June 1, 1921. Serial No. 474,231.

To all whom it may concern:

Be it known that I, CHARLES E. McMANUS, a citizen of the United States, residing at the borough of Manhattan, in the 5 city, county, and State of New York, have invented certain new and useful Improvements in Locking Attachments for Cork-Rod Bakers, of which the following is a specification, reference being had therein to 10 the accompanying drawings, which form a part thereof.

My invention relates to locking attachments for cork rod bakers, and more particularly to an automatically actuated device adapted to hold the filled and packed tubes in the carriers while they are progressing through the baker or vulcanizer for the purpose of vulcanizing or curing the composition in the tubes while permitting 15 the release of the tubes and their removal 20 from the carrier, while incidently setting the carrier preparatory to the recharging thereof.

In a vulcanizing or baking machine of the 25 character to which my invention relates, tubes packed with composition cork are mounted in movable carriers of the type referred to in my co-pending application Serial No. 473,426 filed May 28, 1921, and are 30 conveyed slowly through a baking or vulcanizing machine in which they are subjected to an elevated temperature. At the receiving end of the baker or vulcanizer, each carrier receives a plurality of tubes which 35 are mounted upon the carrier by hand, the tubes being removed from the carrier, also by hand, at the delivery end of the machine. Since the tubes are subjected to the elevated temperature for an interval between one and 40 three hours according to the binder used in the composition, economy of space demands that the carrier shall follow a sinuous course, upwardly and downwardly, while in the baker or vulcanizer. To avoid the necessity 45 for too close a fit between the ends of the tubes and the carrier plates as well as to allow for expansion of the tubes under the heat of the baker or vulcanizer, I provide each carrier with a locking attachment adapted 50 to be brought across the top of the tubes mounted in the carrier, and thus hold them in the carrier irrespective of the position thereof while passing through the baker or vulcanizer. I also provide means adjacent 55 the receiving end of the vulcanizer adapted

to automatically set the locking attachment as the carrier moves thereinto, thus expediting the charging of each carrier.

At the delivery end, the release of the locking attachment to permit the removal of 60 the tubes, will result in its being positioned with relation to the carrier in a manner to permit its being charged with a fresh supply of tubes.

In this manner no attention to the locking attachment is required of the operator at the charging end of the baker or vulcanizer, and all possibility of the escape of tubes from the carrier while passing 65 through the baker or vulcanizer, is avoided. 70

The construction of the locking attachment is such as to permit its convenient release at the delivery end of the baker or vulcanizer, while ensuring permanency in its 75 positioning when it is either set or released, thus increasing the capacity of the machine by securing uniformity in the conditions of all carriers at the receiving end of the machine.

The invention consists primarily in a locking attachment for cork rod bakers embodying therein the combination with a movable carrier for a plurality of super-imposed tubes, of a rotatable keeper bar carried thereby and movable about an axis at right 80 angles to the axes of the tubes, said keeper bar being adapted to project across the top of the tubes, and an abutment carried by the baker structure positioned at one side of the axis of said keeper bar and in the path of 85 movement thereof, whereby as said keeper bar engages said abutment it will be rotated to position above said tubes to prevent their escape from the carrier while progressing through the baker; and in such other novel 90 features of construction and combination of parts as are hereinafter set forth and described, and more particularly pointed out in the claims hereto appended.

Referring to the drawings, 100
Fig. 1 is a plan view of a fragmentary portion of the carrier mechanism showing three succeeding carriers and their locking attachments, the carrier to the left showing a keeper bar in its inoperative position, the 105 carrier to the right showing a keeper bar in its operative position, and the intermediate carrier showing a keeper bar as it is being automatically moved from its inoperative to its operative position; 110

Fig. 2 is an end view of the locking attachment of the intermediate carrier on the line 2-2 of Fig. 1;

Fig. 3 is a vertical section through the stay rod and locking attachment on the line 3-3 of Fig. 4, the latter being in the inoperative position; and

Fig. 4 is a similar section showing the locking attachment in elevation and in the operative position with relation to the tubes in the carrier, on the line 4-4 of Fig. 1, upon an enlarged scale.

Like letters refer to like parts throughout the several views.

15 Since the present invention relates solely to the means for locking the tubes in the carrier, and since the construction of the carrier is immaterial to the present invention, the showing of the drawings is limited 20 to the construction of the locking attachment and of its actuating means, and the description will also be so limited, with an incidental reference to the construction of the baker and the means for conveying the tubes 25 packed with cork composition therethrough.

In a baker or vulcanizer used in curing 30 or vulcanizing cork rods formed by packing granular cork having a thin coating of a binder adapted to be vulcanized or cured at 35 an elevated temperature, the practice has been to mount upon endless conveyer chains, a sequence of carriers adapted to engage opposite ends of the rod. These carriers are passed through a baking oven or vulcanizer 40 at low speed and in a sinuous course, thus resulting in a frequent change in the position of the carrier so as to necessitate the provision of some means for preventing the packed tubes from falling from the carrier.

45 The carriers are charged with tubes by hand at the receiving end of the baking oven or vulcanizer, and are removed by hand at the delivery end, the locking attachment being made so as to be automatically brought into its operative position and thus obviate 50 likelihood of the feeder neglecting to lock the tubes in the carriers.

The carrier in connection with which a locking attachment made in accordance with 55 my invention is used, includes therein a stay rod a , the axis of which is substantially parallel with the axes of the tubes grouped upon opposite sides thereof in the carrier, the feeding movement of the carrier being 60 at right angles to the axis of said stay rod.

Pivotedly mounted in the stay rod a of each carrier by means of the pivot stem b is a rotatable head c carrying a keeper bar d of a length to extend over and engage the 65 uppermost tubes supported by the carrier, said head being of a height to position the bar in the manner described. The lower face of the head c is curved to conform to the perimeter of the rod a , the curvature 70 of said surface being along two lines at

right angles to each other so that the head c may be locked to hold the keeper bar with its axis parallel with that of the stay rod a or at right angles thereto and to the axes of the tubes, the stem b being capable of longitudinal movement in its bearing in said stay rod to permit the desired rotary movement of said head from the operative to the inoperative position, or vice versa.

75 Encircling the stem b below the rod a is a spring seat forming washer e between which and a washer carried by the lower end of the stem b is seated a coiled spring f having a normal tendency to draw the head c toward the rod a , the tension of this spring being sufficiently light to permit movement of the head c radially of the stay rod a in moving the keeper bar to an inoperative position with relation to the tubes at the discharge end of the oven or vulcanizer. 80 This actuation of the keeper bar d to its inoperative position or with its axis parallel to that of the stay rod a , which is necessary to permit the removal of the packed tubes from the oven or vulcanizer, also positions 85 the locking attachment so that at the receiving end of the machine, it requires no attention by the operator who fills the carriers. 90

95 Carried by the oven adjacent the receiving end of the machine, is an abutment g arranged at one side of the axis of the stem b in a position to be engaged by the keeper bar d after the carrier has been filled and as it is about to enter the oven, thus causing the 100 progress of the carrier and the locking attachment to result in a 90° rotary movement of the stem b , its head c and the keeper bar d as a result of the movement of the carrier.

The packed tubes are shown at h .

105 The operation of the herein described mechanism is substantially as follows:—

In feeding the baker or vulcanizer, the tubes h are mounted in the carriers one at a time, requiring both hands of the feeder. 110 At the delivery end, however, the tubes are removed in bulk, thus, permitting a more rapid discharge of the machine than a charging thereof.

115 By employing an automatic locking attachment, the feeder may mount the tubes in the carriers somewhat more rapidly than would be possible if after each carrier is filled, it is necessary to set the locking attachment by hand, thus permitting a slight increase 120 in the speed of operation of the machine, which in a continuously operating mechanism is a matter of considerable importance. Furthermore, likelihood of the feeder overlooking the locking of the tubes in the carrier is avoided.

125 As each carrier approaches the feeding position, the keeper bar d will be in the position shown to the left of Fig. 1, thus leaving the field about and above the carrier 130

entirely unobstructed, so that the feeder may rapidly mount the tubes therein. As soon as one carrier is completely charged with the tubes containing the cork rods, the feeder may begin charging the next carrier, and as the carrier progresses, the bar *d* at one side of the axis thereof will engage the abutment *g* and be rotated as the carrier moves past the abutment. As the head *c* is rotated with the bar *d*, it will rise against the tension of the spring *f* as a result of the engagement of the opposite walls upon one of the under curvatures of the head *c*, the right angularly arranged curvature co-acting with the stay rod *a* and the spring *f* to complete the desired 90° movement of the head *c*, at the same time engaging the right angular curvature above referred to with the rod *a* so as prevent accidental rotation of the keeper bar while in the oven or vulcanizer.

As each carrier approaches the discharge end of said oven or vulcanizer, the operator at that end of the machine will release the locking attachment by grasping the bar *d*, raising the head *c* against the tension of the spring *f*, giving a manual 90° turn to the bar, and permitting it to drop back into place where it will be locked in its inoperative position. Thereafter he will seize a group of rods and remove them from the carrier and allow the carrier to proceed empty back to the delivery end of the machine. This will not in any way limit the capacity of the machine, as the operator at the delivery end requires less time to remove the tubes than is required by the operator at the receiving end of the baking oven or vulcanizer.

While the carriers are progressing through the oven or vulcanizer, the bar *d* will extend at right angles to the axis of the tubes, and across the top of same so as to prevent the escape of the tubes from the carrier irrespective of the position of the carrier.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:—

1. A locking attachment for cork rod bakers embodying therein the combination with a movable carrier for a plurality of super-imposed tubes, of a rotatable keeper bar carried thereby and movable about an axis at right angles to the axes of the tubes, said keeper bar being adapted to project across the top of the tubes, and an abutment carried by the baker structure positioned at one side of the axis of said keeper bar and in the path of movement thereof, whereby as

said keeper bar engages said abutment it will be rotated to position above said tubes to prevent their escape from the carrier while progressing through the baker.

2. A locking attachment for cork rod bakers embodying therein the combination with a movable carrier for a plurality of super-imposed tubes, of a rotatable head carried thereby and movable about an axis at right angles to the axes of the tubes, a keeper bar carried by said head and adapted to project across the top of said tubes, said head being adapted to co-operate with the supporting means to be held in the set position or in the released position, a spring co-operating with said head whereby movement of said head with relation to its support is permitted to permit rotary movement of said head and said keeper bar, and an abutment carried by the baker structure positioned at one side of the axis of said keeper bar and in the path of movement thereof, whereby as said keeper bar engages said abutment it will be rotated to position above said tubes to prevent their escape from the carrier while progressing through the baker.

3. A locking attachment for cork rod bakers embodying therein the combination with a movable carrier for a plurality of super-imposed tubes having a stay rod with its axis extending parallel to the axes of the tubes, of a keeper bar rotatably mounted upon said rod and movable about an axis at right angles thereto, said keeper bar being adapted to project across the top of the tubes, and an abutment carried by the baker structure positioned at one side of the axis of said keeper bar and in the path of movement thereof, whereby as said keeper bar engages said abutment it will be rotated to position above said tubes to prevent their escape from the carrier while progressing through the baker.

4. A locking attachment for cork rod bakers embodying therein the combination with a movable carrier for a plurality of super-imposed tubes having a stay rod with its axis extending parallel to the axes of the tubes, of a stem rotatably mounted in said rod and having movement about an axis at right angles to the axis thereof, a head carried by said stem, a keeper bar carried by said head and adapted to project across the top of said tubes, the under surface of said head having curved surfaces extending at right angles to each other and adapted respectively to engage the perimeter of said rod, whereby said head and said keeper bar will be held in the set or in the released position, a spring acting upon said stem and against said rod, whereby movement of said head with relation to said rod, and rotary movement of said head and said keeper bar, is permitted, and an abutment carried by the baker structure positioned at one side of

the axis of said keeper bar and in the path of movement thereof, whereby as said keeper bar engages said abutment it will be rotated to position above said tubes to prevent their escape from the carrier while progressing through the baker.

5. A locking attachment for cork rod bakers embodying therein the combination with a sequence of movable carriers each 10 adapted to receive a plurality of superimposed tubes, of a movable member on each carrier adapted to be projected across the top of the tubes at an angle to the axes thereof, and to be manually moved into substantial alignment with the axes of the tubes,

and a fixed member adapted to successively engage said movable members and force them into position above the tubes, whereby the escape of the tubes from the carrier while it is progressing through the baker, is prevented. 20

In witness whereof I have hereunto affixed my signature, in the presence of two subscribing witnesses, this 18th day of May, 1921.

CHARLES E. McMANUS.
